9 Claims. (Cl. 74—585)

This invention relates to compressing tools, particularly of the type adapted for metal working operations such as terminal crimping, rivet setting, bending, and forging. The invention is herein disclosed in an embodiment of a terminal crimping tool, however, it will be apparent that the invention is not limited to this particular type of operation.

Several design and performance requirements of tools of the class to which the instant invention pertains should be appreciated for a full understanding of the objects of the instant invention. In general, compressing tools are employed to perform metal forming operations in which the force required increases as the stroke of the ram proceeds and reaches a maximum level at or near the end of the stroke. It is also desirable in such tools that the compressing dies (e.g. the crimping dies in the case of a terminal crimping tool) be capable of opening or moving apart a substantial distance in order to permit the work piece to be positioned therebetween. Thus, when a tool of this type is actuated, the ram may travel a substantial distance during which it encounters very little resistance and during which it need not therefore develop much thrust. During the final portion of the stroke of the ram, however, the resistance increases abruptly and may reach a substantial level. During this final relatively small portion of the stroke, most of the work which is done during the cycle is accomplished. By way of example, the case of a typical terminal crimping tool can be cited in which a die opening of one-half inch is required to permit positioning of the terminals between the dies. The design of the terminals, however, is such that the actual crimping operation requires only about 0.1 inch of ram travel and during the very last portion of this 0.1 inch of travel, the force developed may go as high as 4000 pounds. It will be apparent upon reflection that similar conditions exist in, for example, rivet setting operations since the resistance to deformation increases as the rivet is deformed and the final portion of the stroke of the riveting die requires a much greater applied force than the initial portion of the stroke. It should be added that a desideratum of these tools is usually small size since the work pieces, for example, terminals or rivets, are usually very small and it is advantageous to have a tool which can be manually held and transported easily to the site of the working operation.

It will be apparent from the foregoing discussion that it would be impractical to mount the ram of a compressing tool directly on a fluid-actuated piston for the reason that a relatively large diameter piston having a long stroke would be required to accomplish a large die opening and furthermore, much of this stroke would be wasted since the maximum force is developed only during the very final stages of the stroke of the ram. Many of the presently available compressing tools therefore provide a force multiplying means between the piston and the ram to achieve a quick take-up during the first portion of the stroke of the piston (i.e. a substantial movement of the ram during the first part of the stroke of the piston) followed by a compressing, or metal working, portion of the stroke during which the piston may move a substantial distance and the ram will move only a relatively short distance but will develop a relatively high thrust. Force multiplying devices of this type have, in the past, quite frequently been provided in the form of a simple

2

slidable cam which engages the ram directly or may engage some intermediate linkage which in turn causes the ram to move. While tools of this type are widely accepted and have proved highly successful, they suffer from the disadvantage of developing relatively high frictional forces, particularly during the final portion of the stroke of the cam. Since the ram thrust reaches very high levels during this final portion of the stroke, the linkage extending from the ram to the piston is also very highly stressed and where the cam or similar device must slide over a bearing surface, very high frictional forces are developed which tend to detract from the useful force and work available on the end of the ram. In many tools, roller bearings have been employed to reduce the frictional forces developed but such arrangements render the tools more expensive to manufacture and undesirably complex.

It is accordingly an object of the present invention to provide an improved tool which obviates, or reduces the effect of, the foregoing problems associated with compressing tools. A further object is to provide a compressing tool having an improved force multiplying linkage between a power source, such as a piston, and a compressing ram. A further object is to provide a tool which is simple in construction and which reduces the effects of friction during the power stroke. A still further object is to provide a fluid-actuated tool in which a small portion of the stroke of the piston is utilized to move the ram a substantial distance leaving a major portion of the stroke of the piston to accomplish the work required of the ram during the stroke. A still further object is to provide a tool having means to ensure that, in every cycle of operation, the ram will travel a predetermined distance to perform a specific operation (such as terminal crimping) before the ram is permitted to return to its starting position.

These and other objects of the invention are achieved in one preferred embodiment comprising a cylinder having a piston therein at one end and having a ram extending from its opposite end. The ram is pivotally connected to one end of a toggle, the opposite end of which is mounted on a fixed pivotal axis. This toggle is normally broken and its knee joint is normally in engagement with the face of a block which in turn has a pivotal connection with the piston. The block, which functions as both the pushing block and a camming block, is mounted by means of parallel links for movement along an arcuate path so that as the piston moves from its normally retracted position, it first pushes the knee joint of the toggle to substantially, but not fully, straighten the toggle links and to achieve a relatively large displacement of the ram. Thereafter the knee joint of the ram contacts a camming surface on the block and during the remainder of the stroke of the piston this camming surface further straightens out the toggle and drives the ram to the limit of its travel. The camming surface of the block is so contoured that it compensates for the arcuate path along which the block itself moves during the stroke.

In the drawing:

FIGURE 1 is a perspective view of a tool in accordance with the invention.

FIGURE 2 is a sectional view of the interior of the cylinder of the tool shown in FIGURE 1 and showing the positions of the parts at the beginning of the operating cycle.

FIGURES 3 and 4 are views similar to FIGURE 2 but showing the relative positions of the parts at an intermediate stage and at the final stage of the operating cycle.

FIGURE 5 is a view taken along the line 5—5 of FIGURE 2.

FIGURE 6 is a perspective view of the camming block which forms part of the invention.

FIGURE 7 is a view taken along the lines 7—7 of FIGURE 5.

FIGURE 8 is a view taken along the line 8—8 of FIGURE 7, and

FIGURE 9 is a graph illustrating the movement of some of the parts during the stroke of the tool.

The disclosed embodiment of the invention, a crimping tool for crimping electrical terminals onto the ends of wires, comprises a cylinder 2 which is adapted to be manually held and which is closed at its upper end by a cylinder head 4 through which the end of a ram 6 extends. Mounted on the upper portion of the tool, by means of ears 8 integral with the cylinder head, is a generally C-shaped tool head 10 having a die holder 11 secured thereto in which upper or fixed crimping dies 16 are mounted. Complementary lower crimping dies 12 are mounted on a die holder 14 which, in turn, is secured to the upper end of the ram, this structure not being shown in FIGURES 2—4 in the interest of simplicity. In use, a terminal is merely positioned on the lower dies and the tool is actuated to drive these dies into engagement with the upper die 16 to crimp the terminal. In the disclosed tool, as in similar types of metal-forming tools, a large die opening is desirable to permit positioning of the work piece between the dies. The present invention concerns the actuating means for the ram 6 and will now be described.

A reciprocable piston 18 is mounted in the lower portion of the cylinder 2, as viewed in FIGURE 2, and a conduit 20 supplies motive fluid to the lower end of the cylinder to drive the piston upwardly. Advantageously, a lever 22 is provided on the exterior of the cylinder for controlling the valve (not shown) by means of which the motive fluid is admitted to, and exhausted from, the cylinder. Piston 18 is normally biased downwardly, as viewed in the drawing, by means of a spring 25 interposed between the face of the piston and a plate 24 which divides the interior of the cylinder into an upper portion, in which the force multiplying linkage is mounted, and a lower portion in which the piston reciprocates. A piston rod 26 is pivotally secured at one end to the piston and has its opposite end received within a slot 27 in a block 28 and is pivotally secured to the block at 29. It will be noted that the lower end of this block, again as viewed in FIGURE 2, projects through an opening in the plate 24 while the upper end thereof is received entirely within the upper portion of the cylinder. A generally U-shaped housing integral with the cylinder head 4 has a web portion 30 conforming to the curvature of the interior of the cylinder wall and has a pair of parallel side walls 32 projecting towards the center of the cylinder. As best shown in FIGURE 5, block 28 is in alignment with this housing so that the central body portion 34 of the block extends between the side walls while the portion 36, which is enlarged, extends laterally so that its sides are coplanar with the external surfaces of the side walls 32. Block 28 is mounted within the cylinder by means of two pairs of parallel links 38, one pair being provided on each side of the block and each end of each link being pivotally secured at 42 to the block and at 40 to the side walls 32.

The lower end of ram 6 is provided with a threaded adapter 43 which has a lower end pivotally connected to a toggle mechanism generally indicated at 46, and 48. As is apparent from FIGURE 5, this toggle mechanism comprises two links 46 and two links 48, the links 46 being mounted on a pin 44, which extends through the ram adapter and through the side walls 32 of the housing as indicated in FIGURES 7 and 8. The lower links 48 of the toggle are received on the lower most one of the pins 40 so that a common pivotal axis is provided for the lower set of links 38 on each side of the block and the lower links 48 of the toggle. The knee joint 52 of the toggle (the common pivotal axis for the links 46, 48) has a

roller 54 in surrounding relationship thereto engageable with the block 28 as described below. The toggle joint is normally biased to the position of FIGURE 2 by means of springs 56 (FIGURES 7 and 8) on each side of the side walls 32 which surround rods 58 extending from the plate 24 to the cylinder head. The right-hand ends of the springs as viewed in FIGURE 8 are connected by means of rods 60 to the end portions of the pin 44 which extend through elongated slots in the side walls 32. This arrangement permits upward movement of the ram and straightening of the toggle as viewed in FIGURE 2 but normally biases the ram and toggle to the position of FIGURE 2. Advantageously a leaf spring 64 is mounted in the housing having an outwardly bent end portion 62 which tends to break the toggle when the parts are in the positions of FIGURE 4. This arrangement causes the toggle to be automatically broken so that the ram can be pulled downwardly by the spring 60 when the block 28 is in its lower position. A set screw 61 is provided in housing 30 to act as a stop for the knee joint as viewed in FIGURE 4.

The block 28 has an inclined leading face 66, which is engageable with roller 52, and a cam surface 68 which is also engageable with the roller. When the block and piston are in their retracted positions as shown in FIGURE 2, the roller bears against the face 66. Upon upward movement of the block and piston, the roller and knee joint of the toggle are pushed causing the toggle to be substantially, but not fully, straightened out until the position of the parts of FIGURE 3 are achieved. Thereafter the roller engages the contoured cam surface 68 so that upon further upward movement of the block the toggle is further straightened out and the ram driven upwardly. It will be noted that the surface 68 is contoured to compensate for the fact that the block 28 moves along an arcuate, rather than a straight-line, path during the stroke of the tool.

In some operations, for example in crimping terminals, it is desirable to provide means to assure that, once a cycle is initiated, the parts will go through a predetermined series of motions and the ram will travel a predetermined distance before the parts can return to their starting positions. In the disclosed embodiment there is provided in the slot 27 a spring biased pawl 70 having an end portion which extends beyond the block and into a recess 74 in a bar 75. This bar is slidably held between the face of the cylinder head 4 and the surface of the plate 24 so that it can move rightwardly and leftwardly as viewed in FIGURE 2 although it is not permitted axial motion. Ratchet teeth 72 on an intermediate portion of the bar are engaged by the pawl during upward movement of the block and prevent return motion of the parts until the pawl enters the uppermost notch 76 in the bar which permits reorientation of the pawl and downward movement of the block. It will be apparent from FIGURE 5 that the bar itself is held in place by means of a channel 78 movable with respect to the bar and secured by means of fasteners on the lower surface of the block as viewed in FIGURE 5.

The movements of the parts during the operating cycle have been explained above and are apparent from FIGURES 2—4. As the ram moves upwardly, during a relatively small portion of the stroke of the piston, the knee joint 54 is pushed (rather than cammed) and moves rightwardly. This initial movement of the piston results in substantial travel of the ram because of the nature of the toggle linkage between the block and the ram. After the roller 54 has encountered the cam surface 68 of the block the roller is cammed rightwardly and during this interval relatively high pressures or unit stresses can be developed thereby to impart relatively high thrust to the end of the ram for the crimping or other operation. The relationships are shown in the graphs of FIGURE 9 wherein it can be seen that the ram travels a substantial distance during the very first portion of the travel of the

piston, and then, the ram travels the remaining relatively small portion of its stroke while the piston travels a relatively long distance which remains for its stroke. The effect of this arrangement is that the work available by the travel of the piston is substantially all usefully employed in the crimping operation and is not wasted in merely driving the ram upwardly against substantially zero resistance.

It will be noted that the surface 66 of block 28 slopes downwardly and away from the toggle as viewed in FIGURE 2. This feature of disclosed embodiment provides the extremely quick take-up described above and further illustrates the fact that during initial upward movement of the block, the knee joint is not cammed rightwardly, in the usual sense, but is pushed and moves rightwardly of its own accord. It will be apparent that the ratio of ram movement to piston movement can be varied by changing the inclination of this surface 66.

Other advantages to the instant embodiment are that the linkage itself is relatively simple and durable and is not subject to the development of high frictional forces as is the case with a simple sliding cam. This advantage of low frictional losses is achieved by virtue of the parallel link type mounting for the block 28 in that, as a general rule, frictional losses in rotating parts are substantially lower than frictional losses in reciprocating parts such as slides. Theoretically, the frictional forces developed in a nonperfect journal or pivot pin such as in the instant device are substantially the same as the frictional forces developed between sliding members. As a practical matter, substantial advantages are realized in the rotating part by reason of the fact that the lubrication problem is simplified and the advantages of hydrodynamic lubrication are more easily achieved with rotating parts.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

I claim:

1. A compressing tool comprising a housing, a cam in said housing, said cam being pivotally secured to one end of a link means, said link means being pivotally secured to said housing at its opposite end, means for moving said cam along an arcuate path defined by said link means, a toggle mechanism in said housing having one end pivotally mounted on a fixed axis and having a knee joint in engagement with said cam, a ram, the other end of said toggle being pivotally secured to said ram whereby, upon movement of said cam, said toggle is straightened out and said ram is moved.

2. A compressing tool comprising, a reciprocable actuating means, a rod pivotally secured at one end to said actuating means, a block pivotally secured to the other end of said rod, said block being pivotally mounted on the end of link means for movement along an arcuate path upon reciprocation of said actuating means, a normally broken toggle disposed adjacent said block and extending alongside said rod and block when the links of said toggle are in alignment with each other, one link of said toggle being pivotally mounted at one end on a fixed pivotal axis, the other link of said toggle being pivotally secured to a reciprocable ram, the knee joint of said toggle having a roller thereon, said block having a leading face which extends substantially transversely of its path of reciprocation, said roller being in engagement with said leading face when said block is in its retracted position and said toggle is broken, said block having a camming surface thereon on its side which faces said toggle whereby, upon movement of said block from

its retracted position, said roller is first pushed by said leading face and said toggle is substantially, but not fully, straightened while said roller moves over said face, and upon further movement of said block, said roller is engaged by said camming surface and said toggle is fully straightened.

3. A compressing tool comprising, a block pivotally mounted on link means for motion along an arcuate path, a normally broken toggle disposed adjacent to said block, said block having a leading face extending substantially transversely of the axis of said toggle when said toggle is straightened, the knee joint of said toggle being in engagement with said leading face when said toggle is broken whereby upon initial movement of said block said knee joint is pushed and said toggle is partially straightened, said block having a camming surface facing said toggle, said knee joint being engageable with said camming surface after said initial movement further to straighten said toggle, one end of said toggle being pivotally secured to a fixed axis, and a compressing ram pivotally secured to the other end of said toggle whereby, upon straightening of said toggle said ram is moved at a decreasing rate of speed and with an increasing force.

4. A compressing tool comprising, a housing, a reciprocable actuating means in said housing, a block in said housing, a rod pivotally connected at one end to said block and at its other end to said actuating means, said block being pivotally mounted within said housing by means of at least one pair of parallel links whereby, upon reciprocation of said actuating means, said block is oscillated along an arcuate path, a toggle in said housing, one end of said toggle being pivotally mounted on a fixed axis and the other end thereof being pivotally secured to a reciprocable ram, said toggle being disposed adjacent to said block and extending alongside said block when the links of said toggle are in alignment with each other, said block having a leading face extending substantially transversely of the axis of said housing and having a cam surface on its side which is adjacent to said toggle, the knee joint of said toggle being in engagement with said leading face when said toggle is broken and said block is in its retracted position whereby, upon movement of said block from its retracted position, said knee joint is pushed by said leading face thereby to substantially, but not fully, straighten said toggle and to drive said ram a substantial distance, and said cam surface subsequently engages said knee joint to further straighten said toggle and to drive said ram a further distance with concomitant development of a high thrust.

5. Apparatus as set forth in claim 4 including a ratchet bar, a pawl on said block engageable with said ratchet bar, and means on said bar permitting reversal of said pawl only after movement of said block through a predetermined distance.

6. Apparatus as set forth in claim 5 wherein said ratchet bar is mounted on said block and said block is movable along the axis of said bar.

7. Motion transmitting means comprising, a toggle, a block disposed adjacent to said toggle, link means pivotally secured at one end to said block and pivotally mounted on a fixed axis at its opposite end, said block having a surface in engagement with the knee joint of said toggle, and means for moving said block along an arcuate path defined by said link means thereby to straighten said toggle.

8. Motion transmitting means comprising a toggle, a block disposed adjacent to said toggle, parallel link mounting means for said block, means for oscillating said block along an arcuate path defined by said parallel link mounting means, said block having a leading face and having a cam surface on its side adjacent said toggle, said leading face being in engagement with the knee joint of said toggle when said toggle is broken and said block is in its retracted position whereby, upon movement of

said block along said arcuate path, said leading face first pushes said knee joint to substantially, but not fully, straighten said toggle, and at an intermediate position of said block, said cam surface engages said knee joint to further straighten said toggle, said cam surface being compensatory of the arcuate path of said block.

9. In a tool having a block movable along an arcuate path, a ratchet bar movable towards and away from said arcuate path and being axially immovable, means on said block for holding said ratchet bar and moving said ratchet bar towards and away from said arcuate path while said block moves along said path, and a pawl on said block engageable with the teeth of said ratchet bar whereby, upon initiation of movement of said block along said arcuate path in one direction, said pawl en-

5

gages the teeth of said ratchet and prevents reverse movement of said block until the last tooth of said ratchet bar is passed.
